UNITED STATES PATENT OFFICE.

HERMAN B. THURSTON, OF CLEVELAND HEIGHTS, OHIO.

LOW-WATER ALARM.

Application filed July 16, 1926. Serial No. 122,916.

This invention relates to a low water alarm for steam boilers and the particular adaptation is designed for use with locomotive boilers. A very essential result, necessary to the success of low water alarms is that it shall sound when there is still water over the crown sheet of the boiler to enable the operator to recover the normal water level, after the alarm has sounded, and before there is 10 likelihood of any danger to the crown sheet from overheating.

Heretofore, numerous attempts have been made to accomplish this result, but the requirements for successful operation on a rail-road locomotive are very difficult to meet. It has been attempted to provide a time interval in the functioning of the alarm in order that it may not sound when only momentarily subjected to low level of water.

In the previous applications of Herman B. Thurston, such for example, as Serial No. 726,711, filed July 18, 1921, and Frank M. Roby, No. 166,126, filed March 19, 1925, it has been sought to accomplish this by means 25 of positioning a thermo-responsive alarm control within a certain zone, and causing it to respond to an average water level irrespective of the surge of water and temporary displacement of the level, by means of retarded thermal conductivity due to the alarm 30 construction.

The present invention is designed on an entirely different, and, I believe, novel principle, whereby the alarm is responsive very accurately to a water level—the average being accomplished by such a time interval by the definite and positive timing of flowing water, determining an arbitrary level of the water controlling the alarm. It is well known that 40 in stopping or even starting a locomotive, particularly on grades, that for brief intervals the water level is radically changed—the body of the water level surging to one end of the boiler. This has made very difficult the 45 causing of alarm to function with certainty, responsive to an average level of an inch or two inches over the crown sheet. At the time when the level of water is approaching the dangerous low level, the fall is quite 50 rapid and further adds to the difficulty of accomplishing the desired result. It has been demonstrated that with the present invention, the alarm may be caused to sound only under actual conditions of danger, due 55 to the fact that it is delayed say, fifty seconds or one minute after the water is below the

critical point at which the alarm functions. The alarm will not sound if the level is only temporarily dropped by surge of the water.

A further object of the invention is to so 60 arrange such an alarm that it may be accessible for easy and convenient inspection, cleaning and replacement of parts. A still further object is to segregate a small portion of the water where its surging movement, due 65 to the movement of the locomotive, is practically eliminated so that the actuating means for the alarm may be independent of any water surge effect.

Other objects and advantages include the 70 construction of such a device, so that it will be simple and certain in operation of its moving parts, and also such that the provision of a means for conveniently testing the alarm may be provided.

Another outstanding advantage of the present low water alarm is that after the alarm is sounded and the dangerous condition has been eliminated by the rise of the water level, the alarm automatically reconditions itself for further response without the attention of the operator. This is an important feature when compared to arrangements, having a fusible metal controlling the alarm, in which cases, it is usually necessary 85 to remove parts of the alarm in order to replace this metal. Therefore, such former alarms would continue to sound as long as there is steam in the boiler after it had once been actuated.

Other advantages and novel characteristics will be made apparent in the following description which relates to the drawings, illustrating a preferred embodiment thereof. The essential novel characteristics are summarized in the appended claims.

In the drawings, Fig. 1 is a cross-sectional diagram of a locomotive boiler, showing the position of this alarm device where usually mounted; Fig. 2 is an enlarged sectional detail of the outer sheet and crown sheet, carrying the alarm device, illustrating the relationship to the water level; Fig. 3 is a plan of the alarm; Fig. 4 is an enlarged transverse section through the same, on a plane indicated by the line 4—4 of Fig. 3; Fig. 5 is a longitudinal section, taken substantially on a plane indicated by the line 5—5 of Fig. 3; Fig. 6 is a section taken longitudinally through the water tube of the alarm, as indicated by the line 6—6 of Fig. 4; Fig. 7 is a sectional plan taken substantially on the

line 7—7 of Fig. 4; Fig. 8 is a section taken on a plane indicated by the line 8—8 of Fig. 4; Fig. 9 is an enlarged longitudinal section of the alarm valve and operating means; Fig. 10 is a sectional detail of the valve actuating means taken as indicated by the line 10—10 of Fig. 9.

Describing more in detail the embodiments shown in the drawings by the use of reference numerals, 1 is the roof sheet of the boiler, 10 2 the crown sheet.

The alarm shown, comprises essentially a head or chamber member 5 constituting a reservoir for water normally forced upwardly to the chamber through the tube 6 having the inner extension 8, leading substantially to the top of the chamber and projecting inwardly, preferably at an angle, as shown, to a point near the crown sheet and below the 20 water level, indicated at W. I prefer to cut the lower end of the tube at right angles to the tube rather than in the plane of the water level.

The shape of the reservoir is preferably 25 that of a substantially flat cylinder, having an outer projecting cavity or chamber at 10 to accommodate and allow for the necessary movement of a float 12, which operates the alarm whistle, indicated at 15, as will be presently described. The main body of the reservoir provides for a predetermined capacity of water which may be drained through a comparatively small opening 20 near the lower part of the reservoir in the member 25. 30 The downwardly projecting portion of the reservoir, as indicated at 11 is flanged with bracket members or ears 23 and is also preferably provided with a beveled surface 24 to provide a tight fit in the opening through 10 the roof sheet. Within this projection, I provide a securing means for the tube 6 in the nature of a member 25, held in threaded engagement with the projection 11 and being threaded to receive the tube 6, projecting upwardly from below and the extension tube 8, 35 threaded into the member from above.

A suitable cover 30 may be provided for an opening in the upper portion of the reservoir, suitably secured as by screws and preferably provided with a threaded boss to receive the removable plug 32 over the end of the tube 8 to permit convenient inspection of the tube. Depending from the cover 30, I provide a downwardly opening yoke 31 in 55 which the float arm 42 may travel and be guided.

In line with the chamber portion 10, is a projection of the reservoir or casing, flanged to receive cover member 35, which in turn, 60 is threaded to receive the nut 34. On the inner side of the cover is preferably an integral ear 39 as shown in Figs. 5 and 9, carrying the pivot 40 for the float arm 42, which in turn, is loosely connected at 44 to a longitudinally movable valve stem 45, actuating

to close the steam passage in the valve member 36. The bell crank portion of the float arm preferably fits over the ear 39 to assure a vertical swinging motion of the float arm.

In operation, assuming that the boiler is 70 filled to a normal capacity of water, this level will be above the lower ends of the tube. As the steam pressure rises, water will be forced upwardly through the tube 6, to the reservoir 75 5, forcing the air therein outwardly, slowly through the alarm until the float rises to close the valve and thereafter, the level of water will rise in the chamber, the air and steam above the water being compressed by boiler pressure until the chamber 80 will be substantially full, maintaining the float buoyant for holding the alarm valve closed.

When the water falls below the lower end of the tube 6, the tube 6 will drain quite 85 quickly and steam passing upwardly through this tube will maintain the boiler pressure above the water in the reservoir while the bulk of the water in the reservoir will flow comparatively slowly through the opening 90 20 in the member 25. The tube 6 therefore, will drain in proportion to the size of the opening 20 and the water in the reservoir will start to lower while the water level in the boiler exposes the end of the tube for a predetermined time, say not less than a minute. Then water in the reservoir will fall to a point where the float opens the valve by withdrawing the valve stem 45, allowing the steam through the tubes 6 and 8, now free of water. 100 to pass from the boiler to the chamber and thence through the valve passages to the whistle, sounding the alarm. This flow of steam, sounding the alarm, will continue as long as the water level in the boiler remains 105 below the end of the tube.

It will be seen, however, that if, due to a temporary surge of water, the lower end of the tube is exposed, the water in the reservoir will start to drain but the alarm will not be sounded until the reservoir is emptied sufficiently to cause the float to fall and when the water returns again, covering the lower end of the tube, the boiler pressure will cause an upward flow again, substantially filling the 110 reservoir as in the first instance. Thus it will be seen that by this means, we introduce into the positive operation of an alarm, the time element by a predetermined rate of flow of a certain amount of water, through a given 115 orifice, to wit the opening 20. Thus the bottom of the tube 6 must be exposed to steam for a predetermined length of time or the equivalent to sound the alarm.

For purposes of testing the alarm at any 120 time, steam may be introduced into the upper portion of the chamber through a pipe 60 shown particularly in Fig. 5 under the control of a hand valve 62. The tube 60 communicates with the interior of the boiler and the 130

valve 62 is closed except for test purposes. Upon opening the valve, the steam entering the top of the reservoir will release the hydrostatic head and permit the water to flow 5 through the opening 20 until the float actuates the stem valve 45, causing the alarm to sound. Upon closing the hand valve 62, the reservoir again fills with water as previously described, raising the float and closing the 10 alarm valve. It will be noted that the construction of the alarm valve is such as to accommodate very convenient inspection, repair or replacement. The float may be replaced or repaired by removal through the 15 openings in the chambers. The tube 8 may be removed at any time through the opening closed by the cover 30. This gives access to the lower tubes to keep them free from boiler scale. The entire device may be very conveniently 20 removed from the exterior. The arrangement of the tubes slanting inwardly as shown, allows the device to be installed adjacent the steam dome if desired and permits installation at a point most convenient at the 25 exterior of the modern locomotive.

I claim:

1. The combination of a boiler having a steam space and a water space, a low water alarm comprising a reservoir and a signal, 30 means responsive to water level and independent of temperature disposed within the reservoir for controlling the actuation of the signal, said reservoir being disposed exteriorly of the boiler and above the water level 35 thereof, means for filling the reservoir when the water level in the boiler rises above an established point and means for draining said reservoir at a given rate when the water level falls below said established point, whereby 40 the alarm operates on successive occasions in response to a predetermined condition of low water.

2. A low water alarm comprising in combination a closed vessel adapted to be secured 45 to the exterior of the roof sheet of a locomotive boiler at a point above the normal water level of the boiler, a conduit extending from the top of the vessel through the roof sheet and into the boiler and terminating at 50 a point of dangerous water level in the boiler, a float disposed within the vessel, a valve controlling the alarm, said valve being actuated by said float and means for successively draining and filling the vessel to successively 55 sound and silence the alarm.

3. The combination of a boiler having a crown sheet and roof sheet, a reservoir secured to the roof sheet above the normal water level of the boiler, a conduit extending to 60 a point above the crown sheet of the boiler at the level of dangerous low water and adapted to be sealed by water of higher level, said conduit leading to the reservoir so that the reservoir is maintained full of water when the 65 conduit is sealed by the water in the boiler,

means for draining the reservoir when the conduit is unsealed, a float in said reservoir, a valve actuated by said float for sounding an alarm, whereby the alarm may be successively sounded at each occurrence of dangerous low 70 water.

4. In a low water alarm, the combination of a boiler having a crown sheet and roof sheet, a closed vessel secured to the roof sheet above the normal water level of the boiler, a conduit 75 extending through the roof sheet to a point above and adjacent the crown sheet, said conduit leading to the vessel so that the vessel is filled with water when the conduit is sealed by the water in the boiler and drained when the conduit is unsealed, a float in said vessel, a valve actuated by said float for sounding an alarm device whereby the alarm may be successively sounded whenever the vessel is drained.

5. The combination of a boiler having a steam space and a water space, a low water alarm comprising a reservoir and a signal, means responsive to water level regardless of temperature disposed within the reservoir 90 for actuating the signal, said reservoir being disposed exteriorly of the boiler and above the normal water level thereof, means for filling the reservoir from the boiler when the water level in the boiler rises above an established point and means for draining said reservoir at a given rate when the water level falls below and remains below the established point, whereby the said signal will be successively actuated in response to low water in 95 the boiler after the level of the water in the reservoir falls below a given height for a given time.

6. In combination with a boiler having a steam space and water space, a low water 100 alarm, comprising a signal and a reservoir and adapted to be mounted on the boiler and having one passageway to the interior of the boiler and another to the signal, said reservoir being positioned above the normal 105 water level of the boiler, the first passageway terminating below the normal water level of the boiler and means including a float associated with the reservoir to control the actuation of the signal dependent upon the water 110 level in the reservoir but independent of the fluid temperature thereof, said water level in the reservoir being maintained by the boiler pressure while the level of the water in the boiler is above the boiler opening of the first 115 passageway.

7. In combination, a boiler structure having a steam space and water space, a low water alarm, comprising a float controlled signal, a reservoir for water to actuate the 120 float, said reservoir being mounted above the normal water level of the boiler, a conduit having an opening terminating within the boiler at a point of dangerous low water level and opening into the reservoir at the top 125 130

thereof, and having a draining opening within the reservoir, and means including a float associated with the reservoir responsive to predetermined amounts of water therein by which to control the signal, whereby the size of the draining opening may determine the length of time required for the signal to respond after the boiler water falls below the conduit boiler opening.

10 8. A method of operating a low water alarm for steam boilers, wherein a predetermined interval of time is obtained as the water in the boiler falls below the danger point, including filling a small reservoir 15 which contains a float for operating the alarm, said reservoir being positioned above the low water level of the boiler by raising water by boiler pressure through a passage terminating at a danger level in the boiler, 20 draining the water in the reservoir at a predetermined rate when the water falls below the terminus of the passage and causing the amount of water in the reservoir to control the condition of the alarm by raising or lowering the float to render it successively either 25 active or inactive.

9. In combination, a boiler having a steam space and a water space, a closed reservoir disposed exteriorly of the boiler and above the water level of the boiler, a float in said 30 reservoir, a valve actuated by said float and controlling an opening in the reservoir, a conduit leading from the top portion of the reservoir through the bottom of the reservoir 35 into the boiler and terminating near the dangerous water level therein, and being adapted to fill the reservoir with water when its lower terminus is sealed, an orifice in the conduit within the reservoir and in the lower portion 40 thereof, the orifice being of such dimension that a given volume of water will pass through it in a certain time, whereby the sealing or unsealing of the terminus of the conduit renders the alarm successively active 45 or inactive.

10. In combination, a boiler, a chamber disposed above the boiler, a conduit leading from the chamber to the interior of the boiler and terminating below the normal water

level of the boiler, an alarm indicating member, and means mounted within the chamber and movable with reference thereto and adapted to be actuated by the rise and fall of water in the chamber for controlling the operation of said member.

11. In combination, a boiler, a chamber disposed above the boiler, a conduit leading from the chamber to the interior of the boiler and terminating below the normal water level of the boiler, an alarm indicating member, means within the chamber and adapted to be moved with reference to the chamber by the rise and fall of water in the chamber for controlling the operation of said member, and other means connected to the chamber and to a source of steam supply for enabling said first mentioned means to be actuated for operating said member under conditions simulating normal operation thereof under low water conditions in said boiler.

12. The combination of a boiler, a chamber disposed at a higher level than the normal water level of the boiler, a float in the chamber, an alarm signal, there being a valve disposed between the chamber and the signal, 75 said float being arranged to close the valve when the float rises and to open the valve when the float drops, and a conduit leading from the chamber into the boiler to the low water level of the boiler.

13. The combination of a boiler, a chamber disposed at a higher level than the normal water level of the boiler, a float in the chamber, an alarm signal, a valve disposed between the chamber and the signal, said float 85 being arranged to close the valve when the float rises and to open the valve when the float drops, and a conduit leading from the chamber into the boiler to the low water level of the boiler, said conduit having an opening within the chamber higher than the center of the float and having another opening in the chamber lower than the center of the float.

In testimony whereof, I hereunto affix my 95 signature.

HERMAN B. THURSTON.
